DEVICE FOR ROCKING CRIBS

William B. Hayes, Los Angeles, Calif.

Application May 24, 1950, Serial No. 163,947

4 Claims. (Cl. 5—109)

1

My invention consists in a new and useful improvement in devices for rocking cribs. My improved device is so designed that an ordinary crib can be equipped to be rocked by electric power with the flexibility of control characteristic of such power. The device can be used with cribs having either permanently or removably attached rockers. Since it is obvious that a larger force is required to overcome the inertia of the crib at rest to initiate the rocking of the crib than the force required to maintain constant the rocking of the crib after its inertia is overcome, the problem presented regarding the required power out-put of the electric motor supplying the force to rock the crib must be solved. A motor having the power out-put required to overcome the inertia has objectionable weight and cost, and is obviously unnecessary for maintaining constant the rocking of the crib. Conversely, a motor having a power out-put sufficient only to maintain constant the rocking of the crib is inadequately powered to initiate the rocking, thus preventing the automatic initiation of operation of the device when the motor is energized. My invention constitutes the solution of this problem by utilizing a prime moving having a power out-put sufficient only to maintain constant the rocking of the crib after its inertia is overcome, and resilient means having sufficient resiliency to produce a torque to overcome the inertia. Thus my improved device automatically initiates operation when the motor is energized.

While I have illustrated in the drawing and hereinafter fully describe a specific embodiment of my invention, it is to be distinctly understood that I do not consider my invention to be limited to said specific embodiment but refer for its scope to the claims appended hereto.

In the drawings:

Fig. 1 is a transverse vertical section of a crib provided with my improved device, a portion of the crib being broken away.

Fig. 2 is an enlarged detail, partly in section, of the resilient member of the device shown in Fig. 1.

Fig. 3 is an enlarged detail of the connected shaft and crank of the driving mechanism.

Fig. 4 is an enlarged vertical section on the line 4—4 of Fig. 1, in the direction of the arrows.

In the device shown in the drawing, the rockers 5 of the crib C-1 rest upon any suitable supporting medium S, such as the floor of a room. The legs 7 of the crib C-1 are mounted on the rockers

5 by means of sockets 8 (Fig. 4), the rockers 5 being clamped in seats 8-a by wing-bolts 8-b and the legs 7 being clamped in seats 8-c by wing-bolts 8-d. A suitable electric motor M-1 with reduction gearing G-1 having a driven shaft 9 is fixed on the bottom of the crib C-1 intermediate the two legs 7 on one side of the crib C-1. It is obvious that a counterpoise (not shown) can be mounted on the other side of the crib to preserve its equilibrium. A crank 12 is adjustably mounted on the shaft 9 by a sleeve 10 with a set-screw 10-a and having a transverse bore 11 in which is slidably the crank 12 with set-screw 11-a. The arm 12-a of the crank 12 mounted in sleeve 10 is normal to shaft 9 and the arm 12-b of crank 12 is normal to arm 12-a and parallel to shaft 9. On the end of arm 12-b there is a trunnion 12-c on which is pivoted the upper end of a pitman 18. A nut 12-d and a washer 12-e on the bolt 12-f serve to retain the pitman 18 on the crank 12, normal to arm 12-b. The pitman 18 is slidably received in a sleeve 19, its end in the sleeve 19 bearing on one end of a coil spring 20 which has its other end protruding from the sleeve 19 and fixed to a base plate 21 resting on the supporting medium S. A pin 22 transfixing the sleeve 19 and passed transversely through spring 20 closely adjacent its end fixed to plate 21 serves to so attach the sleeve 19 and spring 20 as to space sleeve 19 from the plate 21.

I will now describe the use and operation of my improved device. The force transmitted from the motor M-1 by the gearing G-1 causes the crank 12 to press pitman 18 into the sleeve 19 to compress the spring 20 which, when sufficiently compressed, causes pitman 18 to re-act to overcome the inertia of the crib C-1 and move upwardly the side of the crib C-1 to which the motor M-1 is fixed. Successive revolutions of the crank 12 cause increasing movement of the crib C-1 until its normal oscillatory motion is produced by the force of the motor M-1, the spring 20 being no longer distorted.

Having described my invention, what I claim is:

1. In a device for rocking a crib which has rockers enabling it to rock and resting on a fixed supporting medium for the crib, the combination of a prime mover supported by the crib; a reciprocal member attached to and driven by said prime mover; and resilient means associated with said member and so interposed between the crib and said medium as to convert the reciprocating motion of said member into rocking

motion of the crib, said prime mover having a power out-put sufficient only to maintain constant said rocking motion after the inertia of the crib is overcome, and said resilient means having such a degree of resiliency as to overcome said inertia.

2. In a device for rocking a crib having rockers enabling it to rock, the combination of a prime mover mounted on the crib; a reciprocable member connected to and driven by said prime mover; a fixed re-action member; and resilient means, connecting said members, for converting the reciprocating motion of said reciprocable member into rocking motion of the crib.

3. In a device for rocking a crib having rockers enabling it to rock, the combination of a prime mover mounted on the crib; a reciprocable member connected to and driven by said prime mover; a fixed re-action member; and resilient means, connecting said members, for converting the reciprocating motion of said reciprocable member into rocking motion of the crib, said prime mover having a power out-put sufficient

only to maintain constant said rocking motion after the inertia of the crib is overcome, and said resilient means having sufficient resiliency to produce a torque to overcome said inertia.

5 4. In a device for rocking a crib having rockers enabling it to rock, the combination of a driven shaft, journaled on the crib; a crank adjustably mounted on said shaft; a pitman pivoted on said crank; a fixed re-action member; and a 10 resilient member connecting said pitman and said re-action member.

WILLIAM B. HAYES.
